COVERED JOINT HINGE

Joseph Soss, Roselle, N. J.

Application June 4, 1935, Serial No. 24,799

12 Claims. (Cl. 16—191)

This invention relates to what are commonly termed covered joint hinges designed primarily for use in connection with motor vehicles wherein the joint of the hinge is partially concealed and protected against the elements; and the object of the present invention is to provide means for enlarging upon the bearing or supporting area of a hinge butt upon its support to provide a more secure attachment to the support and to eliminate to a greater degree, the stress or strain upon the screws or bolts employed in attaching the butt to its support. In other words, the object of my invention is to provide one or more large portions of the hinge butt, within the boundaries of the support, with a projecting flange or flanges which extend beyond the normal boundaries of a conventional attaching plate of the butt onto an adjacent surface of the support; a further object being to provide a hinge butt, the hood portion of which includes an extending top and bottom wall providing a cover for the edges of both butts of the hinge outwardly of the respective supports when the hinge is in closed position, and further in stamping or forming from the waste metal of the blank necessary to construct a hinge of this type, the additional bearing or reinforcing flanges at the upper and lower edges of the butt; a further object being to provide a hinge butt having the reinforcing and bearing portions defined wherein the butt is composed of separate sheet metal parts arranged one directly upon the other and wherein one part constitutes the hood or cover for the joint of the hinge; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

45 Fig. 1 is a sectional plan view showing a hinge made according to my invention mounted in connection with a stationary support and swinging member.

50 Fig. 2 is a face view of one butt of the hinge indicating the other butt in an open position and partly in section; and,

Fig. 3 is a perspective view of the hinge detached with the butts in open position.

In the construction shown, I provide a hinge 55 consisting of a hood butt part 5 commonly re-

ferred to as the female member of the hinge and a butt part 6 commonly referred to as the male member of the hinge. The butt 5 is composed of an inner part 7 having at one end portion thereof curled pintle bearings 8 at the upper and lower edges thereof and an outer part or shell 9 having a curved hood portion 10 at one end thereof which partially encircles the bearings 8 and which includes, in the construction shown, top and bottom walls 11, 11a which extend inwardly to the desired degree to meet the outer surface 12 of the support 13 so as to cover the edge portions of the butt 6 when said butt is in closed position as is indicated in Fig. 1 of the drawing. The pintle pin 14 of the hinge extends through the top and bottom plates 11, 11a, the pintle bearings 8 and the curled pintle bearings 6a of the butt 6 to provide the hinge mounting of said butts 5 and 6 one with respect to the other.

Heretofore, in the construction of hinges of the type under consideration and especially butts similar to the butt 5 herein disclosed, it has been customary to cut away the side edges of the shell part 9 inwardly of the inner ends of the walls 11, 11a. Instead of destroying or disposing of this waste material, it is the purpose of my invention to shape or bend such side portions to form laterally extending attaching and reinforcing flange portions 15, 15a at the inner ends of the walls 11, 11a and portions 16, 16a extending longitudinally of the butt inwardly of the flanges 15, 15a. These flanges extend onto the surfaces 12a and 13a respectively of the support 12, 13 in the manner indicated in Fig. 1 of the drawing and may be welded, riveted or otherwise secured thereto, or, if desired, may simply be disposed adjacent such surfaces to provide a wider bearing area of the butt upon the support. I may also provide the inner end of the outer shell part 9 with a projecting flange 17 adapted to overlie the inner surface 13b of the support 13 to also aid in this mounting and to further reinforce the attachment of the butt to the support. It is understood in this connection that screws or other devices may be passed through the apertures 18 provided in the attaching plate portion of the butt 5 or the respective parts thereof.

While I have shown the butt 5 as provided with flanges 15, 16 and 17, it will be understood that all of these flanges need not be employed in every installation, as in some cases, one flange alone, for example the flange 15, may be employed, or the flange 16. By reason of the manner of constructing these flanges, the same may be cut up

into any desired length or to any number of parts to suit specific requirements in the different installations.

By constructing the hinge butt in the complete manner shown, from this position it may be further shaped or formed to suit specific requirements, and these may be varied as to the opposed edges of the butt. My invention is not limited to the particular type and structure of the hinge butt herein disclosed, as this is merely illustrative of one method of carrying the invention into effect. It will be understood that the length of the plate 11 and its companion plate 11a may be varied to suit the requirements in different installations.

Having fully described my invention, what I claim as new and desire to secure by Letters Patent, is:—

1. A hinge comprising two butts having inter-engaging pintle bearings with a pintle coupling said bearings together, one of said butts including a side wall extending from the pintle bearing end portion thereof and overlying the edge of the other butt when said butts are in closed position, and said side wall including an angularly projecting flange disposed at the inner end of said wall and adapted to engage the support in connection with which the butt is mounted to reinforce the mounting of the butt in said support.

2. A hinge comprising two butts having inter-engaging pintle bearings with a pintle coupling said bearings together, one of said butts including a side wall extending from the pintle bearing end portion thereof and overlying the edge of the other butt when said butts are in closed position, said side wall including an angularly projecting flange disposed at the inner end of said wall and adapted to engage the support in connection with which the butt is mounted to reinforce the mounting of the butt in said support, and said flange being disposed in a plane transversely to the longitudinal plane of the butt.

3. A hinge comprising two butts having inter-engaging pintle bearings with a pintle coupling said bearings together, one of said butts including a side wall extending from the pintle bearing end portion thereof and overlying the edge of the other butt when said butts are in closed position, said side wall including an angularly projecting flange disposed at the inner end of said wall and adapted to engage the support in connection with which the butt is mounted to reinforce the mounting of the butt in said support, said flange being disposed in a plane transverse to the longitudinal plane of the butt, and another projecting flange arranged longitudinally of the butt inwardly of said first named flange.

4. A hinge comprising two butts having inter-engaging pintle bearings with a pintle coupling said bearings together, one of said butts including a side wall extending from the pintle bearing end portion thereof and overlying the edge of the other butt when said butts are in closed position, said side wall including an angularly projecting flange disposed at the inner end of said wall and adapted to engage the support in connection with which the butt is mounted to reinforce the mounting of the butt in said support, said flange being disposed in a plane transverse to the longitudinal plane of the butt, another projecting flange arranged longitudinally of the butt inwardly of said first named flange, and the inner end of the butt having a laterally extending flange intermediate side edges thereof.

5. A hinge comprising two butts having inter-engaging pintle bearings with a pintle coupling said bearings together, one of said butts including top and bottom walls extending from said pintle bearings and overlying the edges of the other butt when said butts are in closed position, and the upper and lower edges of the first named butt having outwardly projecting flanges.

6. A hinge comprising two butts having inter-engaging pintle bearings with a pintle coupling said bearings together, one of said butts including top and bottom walls extending from said pintle bearings and overlying the edges of the other butt when said butts are in closed position, and the upper and lower edges of the first named butt having outwardly projecting flanges arranged transversely to the longitudinal plane of the butt.

7. A hinge comprising two butts having inter-engaging pintle bearings with a pintle coupling said bearings together, one of said butts including top and bottom walls extending from said pintle bearings and overlying the edges of the other butt when said butts are in closed position, and the upper and lower edges of the first named butt having outwardly projecting flanges arranged transversely to the longitudinal plane of the butt as well as longitudinally thereof.

8. A hinge comprising two butts having inter-engaging pintle bearings with a pintle coupling said bearings together, one of said butts including top and bottom walls extending from said pintle bearings and overlying the edges of the other butt when said butts are in closed position, the upper and lower edges of the first named butt having outwardly projecting flanges arranged transversely to the longitudinal plane of the butt as well as longitudinally thereof, and said butt comprising inner and outer parts, the outer part including a hood portion partially concealing the pintle bearings of said butts.

9. A hinge comprising two butts having inter-engaging pintle bearings with a pintle coupling said bearings together, one of said butts including top and bottom walls extending from said pintle bearings and overlying the edges of the other butt when said butts are in closed position, the upper and lower edges of the first named butt having outwardly projecting flanges arranged transversely to the longitudinal plane of the butt as well as longitudinally thereof, said butt comprising inner and outer parts, the outer part including a hood portion partially concealing the pintle bearings of the butts, and said top and bottom walls being continuous with said hood portion.

10. A covered joint hinge of the class described, one of the butts of which comprises a curved hood portion having pintle bearings within said hood portion and top and bottom walls continuous with the hood portion, and said top and bottom walls having projecting flanges forming added bearing or supporting surfaces for mounting and securing the butt in connection with a support.

11. A covered joint hinge of the class described, one of the butts of which comprises a curved hood portion having pintle bearings within said hood portion and top and bottom walls continuous with the hood portion, said top and bottom walls having projecting flanges forming added bearing or supporting surfaces for mounting and securing the butt in connection with a support, and said flanges being disposed transversely to the longitudinal plane of the butt.

12. A covered joint hinge of the class described,

one of the butts of which comprises a curved hood portion having pintle bearings within said hood portion and top and bottom walls continuous with the hood portion, said top and bottom walls having projecting flanges forming added bearing or supporting surfaces for mounting and securing the

5 butt in connection with a support, said flanges being disposed transversely to the longitudinal plane of the butt, and said butt being composed of inner and outer parts arranged one directly upon the other and secured together.

JOSEPH SOSS.
